GASOLINE SERVICE STATION ISLAND

Eliot F. Noyes, Canaan, Conn., assignor to Mobil Oil Corporation, a corporation of New York

Filed Apr. 10, 1969, Ser. No. 16,680

Term of patent 14 years

Int. Cl. D10—99; D26—03
U.S. Cl. D52—2

FIG. 1

FIG. 2

FIG.3

FIG.4

FIG. 1 is a front perspective view of one embodiment of a gasoline service station island.

FIG. 2 is a front perspective view of another embodiment of a gasoline service station island.

FIG. 3 is a front view of the FIG. 1 embodiment; and FIG. 4 is a top view of the FIG. 1 embodiment.

The embodiments of FIGS. 1 and 2, as seen in rear perspective, are substantially mirror images of the structure shown in FIGS. 1 and 2, respectively.

I claim:

The ornamental design for a gasoline service station island, as shown and described.
